ATTORNEYS'

UNITED STATES PATENT OFFICE

JOHN MAGEE, OF DETROIT, MICHIGAN

PISTON RING

Application filed January 9, 1929. Serial No. 331,272.

The invention relates to piston rings and more particularly to the type of ring designated as an oil control ring.

The object of the invention is to provide an improved construction adapted to better perform the functions of an oil control ring and so designed as to lend itself readily to commercial production.

Another object is to construct an oil control ring in such a way as to prevent the formation of carbon in the slots extending through the ring.

These and other objects are attained by providing the novel construction hereinafter more fully described and illustrated in the accompanying drawings, wherein—

Figure 1 is a side view of the ring showing the joint between the free ends thereof;

Figure 2 is another side view of the ring looking directly toward one of the slots in the ring;

Figure 3 is a view through the middle section of the ring, a portion being illustrated in elevation;

Figure 4 is a cross section on the line 4—4 of Figure 3;

Figure 5 is another section on the line 5—5 of Figure 3;

Figure 6 is a side view of the ring arranged to illustrate the arrangement of the slots therein.

The piston ring 10, as illustrated in the accompanying drawings, is of the usual split type having a suitable lap joint between the free ends of the ring which, as shown, comprise the cooperating step portions 11 and 12. In cross section the ring is of generally rectangular shape, as shown in Figure 4, the upper outer edge being preferably beveled at 13. Between the upper and lower faces 14 and 15 of the ring are arranged a series of slots 16 which are constructed in such a manner as to impart particularly desirable characteristics to the ring. The slots 16 start at a point adjacent to the split ends of the

ring and continue around the ring in a continuous series. Each slot has an upper plane surface 17 extending perpendicularly to the outer cylindrical face 18 of the ring. The lower face 19 of each slot is also a plane and extends at an angle to the outer face of the ring as indicated in Figure 5. The slot in cross section gives the appearance of a wedge. 21 represents the bottom surface which extends as a chord across the circular ring and intersects the inner cylindrical wall 20 to form a perforation 22.

The walls 21 of adjacent slots are arranged to intersect at a point within the outer periphery of the ring as indicated at 23, thereby serving to connect the two adjacent slots with a groove as clearly indicated in Figure 4. In other words, the adjacent slots 16 slightly overlap to form a connecting groove 24.

It will be observed that while the bottom surface 19 of each slot is a plane surface, the line of intersection 25 with the outer periphery 18 of the ring is a curved line as shown in Figures 2 and 6.

The slots 16 are symmetrically arranged around the periphery of the ring and in the construction illustrated there are eight slots all overlapping to form connecting grooves. The slots adjacent the split ends of the ring do not overlap but terminate at the points 27 and 28, respectively, leaving unslotted portions 29 and 30. For this reason the groove which encircles the entire circumference of the ring, except for the split ends, is sealed adjacent the ends, thus preventing leakage at this point.

The upper surfaces 17 of the slots being at an angle of 90° with the outer cylindrical surface 18 present a sharp edge to the cylinder wall causing the surplus oil on the walls of the cylinder to be scraped off on the downward stroke of the piston. The arrangement of the bottom wall 19 of the slots at an angle of less than 90° with the outer peripheral surface is particularly ad-

vantageous for the reason that this construction eliminates carbon in the ring slots and readily redistributes the accumulated oil to the cylinder walls.

5. What I claim as my invention is:

5. 1. A piston ring provided with a series of circumferentially spaced slots overlapping at the outer wall of the ring to form a continuous circumferential groove.

10. 2. A piston ring provided with a series of circumferentially spaced slots overlapping at the outer wall of the ring to form a continuous circumferential groove, said slots extending through the inner wall of the ring to form a series of apertures.

15. 3. A piston ring provided with a series of circumferentially spaced slots overlapping at the outer wall of the ring to form a continuous circumferential groove, said slots having diverging boundary walls.

20. 4. A piston ring provided with a series of circumferentially spaced slots overlapping at the outer wall of the ring to form a continuous circumferential groove, the upper surface of each of said slots being parallel to the faces 25 of the ring and the lower surface of each slot extending at an angle to the upper surface.

25. 5. A piston ring provided with a series of circumferentially spaced slots overlapping at the outer wall of the ring to form a continuous circumferential groove, the upper surface of each slot extending at an angle of 90° to the outer surface of the ring and the lower surface of each slot extending at an angle 30 less than 90° to said outer surface.

35. 6. A piston ring provided with a series of circumferentially spaced slots overlapping at the outer wall of the ring to form a continuous circumferential groove, said slots having flat bottom portions extending across the arc 40 of said ring and intersecting the inner surface of said ring to form apertures through the ring.

45. 7. A piston ring having a series of slots in the outer cylindrical wall, said slots having a flat bottom surface extending between two points on the outer peripheral wall, said bottom surface being cut away between the ends thereof where its plane intersects the inner 50 wall of the ring.

55. 8. A piston ring having a series of slots in the outer cylindrical wall, said slots having a flat bottom surface extending between two points on the outer peripheral wall, said bottom surface being cut away between the ends thereof where its plane intersects the inner wall of the ring and the bottom surfaces of adjacent slots intersecting at a point within the outer circumference of the ring, thereby 60 forming a continuous groove around said ring.

65. 9. A piston ring having a series of slots in the outer cylindrical wall thereof, each slot having a flat upper surface extending at an angle of 90° with the outer wall of the ring,

each slot having a lower surface lying in a plane extending at an acute angle to the plane of the upper surface, each groove also having a flat bottom surface, the bottom surfaces of adjacent slots intersecting within the periphery of said ring forming a continuous groove, each slot intersecting the inner periphery of said ring to form an aperture through the ring and the slots at the split ends of said rings terminating at a point spaced from the ends of said ring.

In testimony whereof I affix my signature.

JOHN MAGEE.
